(57) **CLAIM**

We claim the ornamental design for an vertical takeoff and landing flying automobile, as shown and described.

DESCRIPTION

FIG. 1 is a rear top perspective view of a vertical takeoff and landing flying automobile showing my new design; FIG. 2 is a rear perspective view thereof, shown in an alternate configuration of use, with wings partially extended; FIG. 3 is a rear perspective view thereof, shown in an alternate configuration of use, with wings and rear tail fully extended;

FIG. 4 is a front view thereof;

FIG. 5 is a back view thereof;

FIG. 6 is a top view thereof;

FIG. 7 is a left side view thereof;

FIG. 8 is a right side view thereof;

FIG. 9 is a left side view thereof, with rear tail retracted;

FIG. 10 is a left side view thereof, shown in an alternate configuration of use with engines vertical;

FIG. 11 is a left side view thereof, shown in an alternate configuration of use with engines tilted;

FIG. 12 is a top perspective view of the vertical takeoff and landing flying automobile shown in an alternate configuration of use with engines partially retracted into body of aircraft and wings fully retracted;

FIG. 13 is a top perspective view thereof, with wings and engines fully retracted into body of the aircraft;

FIG. 14 is a front view thereof;

FIG. 15 is a rear view thereof;

FIG. 16 is a top view thereof;

FIG. 17 is a left side view thereof;

FIG. 18 is a right side view thereof;

FIG. 19 is a rear perspective view of the vertical takeoff and landing flying automobile of FIG. 1 shown in an alternate configuration of use, with parachute deployed; and,

FIG. 20 is a bottom perspective view of the vertical takeoff and landing flying automobile shown in FIG. 2.
